CLEMMA R. RANEY, OF CHICAGO, ILLINOIS, ASSIGNOR TO INTERNATIONAL HARVESTER COMPANY OF NEW JERSEY, A CORPORATION OF NEW JERSEY.

SHOCKING-MACHINE.

1,242,112.

Specification of Letters Patent.

Patented Oct. 2, 1917.

Application filed January 17, 1913. Serial No. 742,535.

To all whom it may concern:

Be it known that I, CLEMMA R. RANEY, a citizen of the United States, residing at Chicago, in the county of Cook and State 5 of Illinois, have invented certain new and useful Improvements in Shocking-Machines, of which the following is a full, clear, and exact specification.

My invention relates to shocking machines.

It has for its object to improve and simplify the construction and operation of a shocking machine in such a manner that the same adjusts itself automatically to produce 15 an improved shock of uniform size under varying grain conditions, and at the same time is of a simple and rugged construction which may be readily and cheaply manufactured. I attain this object by providing 20 improved means for delivering and discharging the sheaves, and improved controlling mechanism coöperating with the same in an improved manner.

In order to fully and clearly disclose my 25 invention, I have illustrated in the accompanying drawings one embodiment which it may assume in practice. It is to be understood, however, that the construction shown may be modified without departing 30 from the spirit of my invention.

Figure 1 is a top plan view of the shocker; Fig. 2 is a side elevation of the same;

Fig. 3 is a rear view of the same;

Fig. 4 is a top plan view of a portion of 35 the sheaf delivering mechanism;

Fig. 5 is a detail view of a portion of the mechanism shown in Fig. 4;

Fig. 6 is a detail view of a portion of 40 the means operating the sheaf delivering arm;

Fig. 7 is a detail view of one of the means for limiting the movement of the said arm;

Fig. 8 is an elevation of the shock discharging trip and its operating mechanism;

Fig. 9 is a sectional view taken on a vertical plane longitudinally intersecting the shaft carrying the sheaf delivery arm.

The shocker shown is of the general type described in my co-pending application Serial No. 573,106 filed July 21, 1910, and is provided with automatic mechanism for oscillating the pivoted sheaf delivering member 1, automatic mechanism for laterally de-

flecting the same as it is moved to sheaf discharging position over a cradle 2, and automatic coöperating mechanism operable when the sheaves in the cradle have reached a predetermined bulk to compress, bind and discharge the latter from the cradle 2; all of said coöperating mechanisms being carried upon a shocker frame 3 provided with suitable controlling mechanism and driven through suitable power connections 4 from a suitable source of power; as, for instance, the main wheel of a harvester.

I will first describe the mechanism which actuates the sheaf delivery member 1 during the operation of filling the cradle 2.

Mechanism for operating the sheaf delivering member.

This mechanism is operated from the power shaft 4 through suitable bevel gears 5, a transversely extending shaft 6, and a sprocket and chain connection 7, and acts 75 to oscillate the member 1 alternately in opposite directions from the full line position shown in Figs. 1 and 2 to the dotted line position indicated thereon.

A clutch 8 controls the connection of this 80 mechanism to a stub shaft 9 journaled in bearings 10 upon brackets 11 carried by the front end of the frame 3. At the opposite end of the shaft 9 from the clutch 8 an arm 12 is provided, which is operatively connected to a resilient link 13 pivoted at its upper end to an elongated arm 14 rotatably mounted upon a transversely extending shaft 15, which is, in turn, rotatably mounted upon supports 16 above the brackets 11. Upon 85 one end of this shaft 15 a collar 17 is fixed. This collar is provided with a flared mouth having abutments 18 at its edges adapted to engage with the arm 14 as the latter is moved around by the rotation of the shaft 9. At a point intermediate the ends of the shaft 15 the sheaf delivering member 1 is 90 carried.

This member is shown in the form of a fork, and is pivotally attached at 19 to a 100 collar 20, fixed to the shaft 15 in such a manner that the fork is free to move laterally about its pivot thereon. To accelerate and cushion the movement of this member 1, a plurality of coöperating springs 21 and 22 105 are provided. The spring 21 acts to ac-

celerate the movement of the member 1 toward sheaf delivering position, and also acts to cushion the member as it returns to sheaf receiving position. As shown, this spring 5 is attached at its upper end to an arm 23 rotatable with the rock shaft 15, while at its lower end it is fixed to the front end of the frame 3. (Figs. 1 and 2). The spring 22, on the other hand, acts to accelerate the 10 return of the member 1 from sheaf delivering position, and also to cushion the same as it returns to that position. As shown herein, this spring is carried between the arc-shaped end of an arm 24, rotatably 15 mounted upon the shaft 15, and the lower end of a bracket 25, fixed to the support and having an opening through which the end of the arm is movable when engaged by an L-shaped member 26 rotatable with the 20 shaft 15. It is to be noted that these springs thus coöperate to accelerate the movement of the member 1 between both of its limits of travel and to cushion the same as it approaches its limits of travel.

25 In its sheaf receiving position the sheaf delivering member 1 occupies the position shown in full lines in Fig. 1, wherein its sheaf carrying end rests upon a horizontally disposed bar 27 protruding from the harvester frame. Adjacent the member 1 when in this position, and supported by the arm 27 and the frame 3 in such a position that it is automatically engaged by the sheaves ejected from the harvester as they fall upon 30 the tines of the member 1, is a pivoted tripping member 28 having one or more upwardly projecting arms 29 extending into the path of the sheaves. This tripping member is pivotally connected at 30 to a curved 35 clutch controlling member 31 normally occupying the position shown in full lines in Fig. 1, wherein its extremity engages a finger 32 protruding from the clutch 8 and holds the same in such position that the clutch is 40 normally disengaged from the shaft 9.

45 The operation of this sheaf delivering mechanism is as follows: When a sheaf is dropped upon the tines of the member 1, the trip 29 is thrown about its pivot, throwing the member 31 to the dotted line position in Fig. 1, wherein it rests upon a stop 33 carried by the frame. The clutch 8 is thus 50 automatically thrown into engagement to operatively connect the shaft 6 to the shaft 9 and impart rotation to the latter. The rotation of the shaft 9 is transmitted to the arm 14 by means of the resilient connection 13. This arm is thrown about its pivot on the shaft 15 until one side of the same engages with one of the abutments 18 on the collar 17. Since the sheaf delivering member 1 is fixed to the shaft 15, this rotation of the shaft 15 is imparted to that member, throwing the same about its pivot from the 55 position shown in full lines in Fig. 2 to the 60 position shown in dotted lines therein.

65 position shown in dotted lines therein, wherein the sheaf is delivered to the sheaf receiving cradle 2, and the energy stored in the spring 22 drives the member 1 with an accelerated backward movement. The continued rotation of the shaft 9 in the same direction, through the pivotal connections 13 and 14, causes the arm 14 to engage with the opposite abutment 18 on the collar 17 after a predetermined movement of the arm, 70 whereupon it coöperates with spring 21 and the sheaf delivering member 1 is thrown backward automatically and with an accelerated movement from the dotted line position to the full line position. This operation continues throughout the filling of the cradle, the member 1 being oscillated rapidly between its limits of travel.

75 In order to build a shock in the cradle which is compact, may be more readily 80 bound, and when deposited by the cradle upon the ground is sturdy and well adapted to remain erect, I provide improved mechanism coöperating with the mechanism for oscillating the fork, and operated thereby, 85 for so deflecting the fork during its movement that the sheaves are deposited alternately upon opposite sides of the cradle with their heads converging and their butts diverging.

90 *Means for laterally deflecting the sheaf delivering member.*

95 This mechanism is operatively connected between the sheaf delivering member 1 and the rotating shaft 9 of the sheaf delivering mechanism.

100 A pinion 34 is fixed to the shaft 9 at a point intermediate its bearings and substantially beneath the pivot of the sheaf delivering member 1. This pinion meshes with a pinion 35 of twice its diameter, which is carried by a bracket 36 upon one of the brackets 11. A stud 37 is provided upon one side of this pinion, and a link 38 is pivotally connected therewith. The opposite end of this link is pivotally connected, as shown in Figs. 4 and 5, to an arm 39 rigidly attached to a vertically extending crank shaft 40 journaled to the frame 3 and provided at its 115 upper end with a slotted crank arm 41 disposed substantially at an angle of 90° to the arm 39. The sheaf delivering member 1 is connected to this arm 41 through a slotted member or link 42 fixed to one side of the member 1 and movable upon a pivoted vertically extending bowed or U-shaped member 43 pivoted at its front end to the frame 3 and having a shorter arm 44 attached to the slotted end of the arm 41 so 120 that when the sheaf carrying member 1 is moved about its pivot from sheaf receiving to sheaf discharging position, it is automatically deflected by the movable member 43.

The operation of the deflecting mechanism is as follows: Inasmuch as the pinion 34 is of one-half the diameter of the pinion 35, upon each revolution of the shaft 9 the pinion 34 will move the pinion 35 through one-half of a revolution. By so proportioning the parts that the pinion 34 is rotated through a complete revolution during a complete to and fro movement of the arm 1, it will be seen that when the arm 1 is in a rearmost position the pinion 34 will have moved the pinion 35 through substantially a quarter of a revolution. In this position the pinion 35, through the link 38 and arm 39, turns the arm 41 about its pivot in such a position as to deflect the bowed or U-shaped member 43 about its pivot to one or the other of the positions shown in Fig. 4, and on so doing carries with it laterally the sheaf delivering member 1, which, as heretofore described, is movable laterally about its pivot 19. Thus it is seen that as the arm is swung from sheaf receiving to sheaf delivering position, it is automatically deflected laterally as it moves toward a vertical position in passing to sheaf discharging position, and as it is returned to sheaf receiving position it is automatically deflected in the opposite direction, so that after it passes the vertical position mentioned it again may move in a rectilinear direction to sheaf receiving position. Obviously, this cycle of operation is reversed upon the continued movement of the pinion 35, so that when the next sheaf is delivered by the member 1 the latter is then automatically thrown to the dotted line position shown in Fig. 4, wherein the sheaf is delivered to the opposite side of the cradle 2. Coöoperating with the sheaf delivering mechanism, and operated automatically thereby, is automatic mechanism controlling the sheaf compressing, binding and discharging mechanism, which completes the shocking process.

Mechanism controlling sheaf compressing, binding and discharging mechanism.

This mechanism comprises means, automatically operated when the sheaves in the cradle reach a predetermined size, which control the shock compressing, binding and discharging mechanism.

At the back of the frame 3, and pivoted at one side thereof, I provide a pivoted feeler arm 45, pivoted at 46 to a vertically extending link 47, and provided with an outwardly extending substantially L-shaped arm 48, which is pivoted at 49 to a second link 50. The link 47 extends downward through a slot 51 in the knotted plate 52, and at an angle toward the front of the machine, as shown in Fig. 2. At its lower end it is pivotally connected to a latch member 53 normally engaging the detent 54 of a

clutch 55 which controls the connection of the sheaf compressing, binding and discharging mechanism to the power shaft 4. The other link 50 extends substantially vertically downward and is pivotally connected at its lower end to a crank 56 normally disposed substantially horizontally of the frame 3 and journaled thereon in suitable bearings. A longitudinally disposed arm 57 is rigidly attached to the inner end of the crank 56 and normally occupies the position shown in full lines in Fig. 8, wherein it is protruded at one side of the pinion 35 into the path of a roller 58 carried thereon, so that the pinion 35, on each complete revolution of the latter, acts to move the link 50 upward and depress the feeler arm 45 into the dotted line position shown in Fig. 3.

The operation of this controlling mechanism is as follows: The pinion 35 is rotated through a complete revolution while the sheaf delivering member 1 is passing twice from sheaf receiving to sheaf delivering position and back again to sheaf receiving position. As heretofore pointed out, the member 1 is deflected to one side of the cradle during one backward movement of the same, and during the next backward movement is deflected to the opposite side thereof by the deflecting mechanism heretofore described. It is to be noted that when the roller 58 engages with the end of the arm 57 to depress the feeler arm 45, the sheaf delivering member 1 is at that time returning from delivering a sheaf to the opposite side of the cradle, so that there is no interference between the feeler arm and the sheaf delivering arm. It is further to be noted that during the movement of the sheaf delivering member to the opposite side of the cradle; that is, the side beneath the feeler arm 45, the latter is inoperative and in vertical position, due to the fact that the roller 58 does not at this time engage with the trip or arm 57. When the sheaves in the cradle have reached a predetermined height the free end of the feeler arm 45 engages therewith, throwing itself upward about a pivot on the sheaves and raising the arm 47 to operate the latch 53 and release clutch 55.

Coöoperating with this controlling mechanism and automatically operated thereby through the clutch 55, are the sheaf compressing, binding and discharging mechanisms.

Sheaf compressing, binding and discharging mechanisms.

These mechanisms are of the general type described and claimed in my co-pending application, Serial No. 573,106, filed July 21, 1910.

The sheaf compressing mechanism comprises a compressor arm 59 pivoted to the

frame 3 at one side of the cradle 2 and above the latter, which is operable from the shaft 6 through a cam 60 rotatable with the binder shaft 61. The binder shaft is, in turn, rotated through a chain and sprocket connection 62, a shaft 63 and gears 64 and 65 from the rotating shaft 6 when the clutch 55 is thrown into operation.

The binding mechanism is likewise operated from the shafts 6 and 61 through the gears 64 and 65, shaft 63 and the sprocket and chain connection 62, and comprises a knotted 66 and a movable binding needle 67, the latter being operable from the binder shaft 61 through a suitable link connection 68, 69 and 70, and being movable transversely across the cradle 2 in an opposite direction to the direction of movement of the compressor arm 59.

20 The shock discharging mechanism is likewise operated from the rotating binder shaft 61, and includes a link connection 71 and 72 carried at the end of said shaft, which operates a pivoted dumping arm 73 carried beneath the cradle 2, to turn the roller thereon about its pivot toward a vertical direction to discharging position. As shown in Fig. 1, a spring 74 is provided which automatically returns the cradle 2 to 25 its normal sheaf receiving position.

The operation of these mechanisms is substantially the same as that described in my co-pending application, the compressor arm and binding needle being operated substantially simultaneously to move in substantially parallel planes in opposite directions across the cradle 2 to compress and bind the shock and then automatically returned to their inoperative positions, whereupon the 30 shock discharging mechanism is automatically operated to tilt the cradle 2 about its horizontal pivot and discharge the shock. As heretofore indicated, the cradle is returned to its sheaf receiving position by 45 means of the spring 74.

It is to be understood that with the mechanisms shown herein, I may use means co-operating with the sheaf delivering member 1 and trip 29 to render the sheaf ejecting mechanism of the binder inoperative during the sheaf delivering movement of the fork.

Means rendering binder inoperative.

55 In a preferred form I employ means controlling the connection of the binder clutch and operated by the sheaf delivering arm 1 to automatically render the sheaf discharging mechanism of the harvester inoperative; 60 or, in other words, lock the harvester so that no sheaves are ejected therefrom while the arm 1 is raised from its sheaf receiving position upon the arm 27 projecting from the harvester. This specific mechanism *per se* forms no part of my sole invention, so

that I have accordingly not illustrated it specifically, only illustrating the clutch controlling member 75 thereof in position to be actuated by the arm 1 when moving to or from sheaf receiving position.

70 Co-operating with these mechanisms I likewise use suitable mechanism for rendering the sheaf delivering mechanism inoperative during the discharge of the shock.

Mechanism for rendering sheaf delivering mechanism inoperative.

This mechanism as shown comprises a single spring-pressed arm 76 pivotally attached to the frame and operable by the 80 binder needle links 69 and 70. This arm has a latch 77 at its front end adapted to engage with the finger 32 of the clutch 8, and is automatically operated by the binding mechanism when the latter is actuated to 85 cause its latch 77 to engage with the clutch finger 32 and thus hold the sheaf delivering arm disconnected from the source of power. Obviously, when the binding operation is completed the arm 76 is automatically re- 90 turned to normal position upon the reverse movement of the binding needle.

The operation of the complete machine, with all its co-ordinating and co-operating mechanisms, is as follows:

95

Operation of the complete machine.

The operation of the construction shown is as follows: When a sheaf is ejected from the harvester it strikes the trip arm 29, 100 throwing the operating mechanism of the sheaf delivering member 1 into positive engagement with the power connection. The member is then turned about its pivot to a substantially vertical position. In this position the deflecting means are operated to deflect the arm laterally as it moves downward to the sheaf delivering position; as, for instance, to the dotted line position shown in Fig. 1. Upon the continued rotation of the operating shaft 9 the direction of movement of the arm is reversed, swinging the same back about its pivot through substantially the same path and automatically unlocking the sheaf binder mechanism through the trip 75. This operation continues until the sheaf receiving cradle 2 is filled, the springs 21 and 22 automatically co-operating to accelerate the movement of the member 1 and preventing hammering, 110 etc. As the sheaf delivering member 1 is moved back and forth it not only alternately locks and unlocks the binder mechanism, but is also automatically deflected alternately to opposite sides of the cradle 2, so 115 that the sheaves deposited therein are built up into a very compact shock. The feeler arm 45 is also automatically actuated as every other sheaf is delivered to move downward on one side of the cradle at the same 120 130

time that the member 1 moves rearward from depositing a sheaf on the opposite side of the cradle. When the member 1 deposits its sheaf at the side of the cradle beneath the arm 45, the latter is held in vertical position. Thus this feeler arm acts automatically without interference with the sheaf delivering arm to determine the height of the sheaves in the cradle 2. When the 10 sheaves reach a predetermined height the arm 45 is thrown upward about the sheaves as a pivot, throwing in the clutch 55 and setting in operation the sheaf compressing, binding and discharging mechanisms. These 15 mechanisms are operated automatically in the desired sequence, the compressing and binding mechanism operating substantially simultaneously, and the shock discharging mechanism being then operated. During 20 this binding and discharging operation the member 1 is automatically made inoperative by the member 77. Obviously, after the discharge of the shock the parts are automatically returned to their initial positions so 25 that the operation may be repeated as soon as the cradle has returned to its sheaf receiving position.

It is to be noted that the operation of the sheaf delivering and shocking mechanism, 30 as well as their controlling mechanism, is entirely automatic. Due to the fact that the shocks produced are of uniform size, greater precision and accuracy of the shocking mechanism is obtained and the shocks themselves are of more compact construction, 35 better calculated to stand up in the field, and at the same time are more readily handled when removed from the field, etc. It is to be noted further that the mechanism is 40 adapted to operate under varying grain conditions. For instance, where the grain is light and then heavy, the mechanism automatically compensates for this difference in the grain, always producing a shock of uniform size. Likewise, the distance between 45 the shocks is automatically regulated by the machine itself, so that in working in light grain the distance between shocks is greater than that between shocks in heavy grain. The machine is, further, of a simple and 50 rugged construction and very positive and quick in its action.

While I have described in this application one form which my invention may assume 55 in practice, it is to be understood that the embodiments shown herein for the purposes of illustration are susceptible of being modified without departing from its spirit.

What I claim as my invention, and desire 60 to secure by Letters Patent, is:

1. In a shocking machine, means including a swinging sheaf delivering member for turning the sheaves end for end and building a prostrate shock, and means coöperating 65 therewith independent of the number of bun-

bles for insuring the construction of shocks of uniform size thereby under varying grain conditions.

2. In a shocking machine, shock building means including a swinging shock building member movable back and forth through a path of gradually decreasing length, and means coöperating therewith insuring the construction of shocks of uniform size thereby under varying grain conditions. 70

3. In a shocking machine, shock building means including a swinging shock building member movable back and forth through a path of gradually decreasing length, and means controlled thereby for discharging a shock built by said member when said shock has reached a predetermined size. 75

4. In a shocking machine, shock building means including a swinging shock building member movable back and forth through a path of gradually decreasing length, and shock binding and discharging mechanism coöperating therewith and controlled by the size of the shock built by said member. 80

5. In a shocking machine, shock building means including a swinging shock building member movable back and forth through an arc of gradually decreasing amplitude, and shock discharging mechanism coöperating therewith and controlled by the size of the shock built by said member. 85

6. In a shocking machine, shock building means including a swinging shock building member movable back and forth through an arc of gradually decreasing amplitude, and shock binding and discharging mechanism coöperating therewith and controlled by the size of the shock built by said member. 90

7. In a shocking machine, a swinging sheaf delivering member movable in a fore and aft direction in a substantially upright plane for turning the sheaves end for end, and shock discharging mechanism coöperating therewith and controlled by the size of the shock built by said member. 100

8. In a shocking machine, a shock receptacle, a swinging shock building member movable in a fore and aft direction in a substantially upright plane and depositing sheaves in said receptacle, and automatic shock discharging mechanism coöperating therewith and operable when the shock built thereby has reached a predetermined size. 110

9. In a shocking machine, a swinging sheaf delivery member movable in a fore and aft direction in a substantially upright plane as it builds a shock, and automatic shock discharging and delivery interrupting mechanism coöperating therewith automatically controlled by the size of the shock built by 120 said delivery member.

10. In a shocking machine, a swinging sheaf delivery member movable in a fore and aft direction in a substantially upright plane as it builds a shock, and shock discharging 130

- and delivery interrupting mechanism co-operating therewith automatically operable under varying grain conditions to discharge shocks of uniform size.
- 5 11. In a shocking machine, a swinging shock building member movable in a fore and aft direction in a substantially upright plane as it builds a shock, shock discharging and delivery interrupting mechanism co-operating therewith, and means controlling said mechanism operable when the shock built by said member has reached a predetermined size.
- 10 12. In a shocking machine, a swinging sheaf delivering member movable in a fore and aft direction in a substantially upright plane, and means interrupting the operation of the same when the sheaves delivered thereby have reached a predetermined bulk.
- 15 13. In a shocking machine, a swinging sheaf delivering member movable in a fore and aft direction in a substantially upright plane, and automatic means co-operating therewith interrupting the operation thereof when the sheaves delivered thereby have reached a predetermined volume.
- 20 14. In a shocking machine, a swinging sheaf delivering member movable in a fore and aft direction in a substantially upright plane, and means automatically actuated thereby to interrupt the operation of the same when the sheaves delivered thereby have reached a predetermined height.
- 25 15. In a harvesting machine, a normally prostrate tilting sheaf receiving member, rearwardly movable means disposed in front of said receiving member for carrying sheaves into a prostrate position therein, means controlled by the bulk of the sheaves therein controlling the tilting of said member, and means independent of the sheaves for positively operating said controlling means.
- 30 16. In a harvesting machine, an upwardly and rearwardly tilting sheaf receiving member, rearwardly movable means disposed in front of said sheaf receiving member for carrying sheaves into a prostrate position therein, and means operable in timed relation with said rearwardly moving means controlled by the bulk of the sheaves therein controlling the tilting of said member.
- 35 17. In a shocking machine, an upwardly and rearwardly movable tilting sheaf receiving member, means disposed in front of said sheaf receiving member and movable rearwardly and downwardly into said receiving member for depositing therein sheaves in prostrate position, and means controlled by the volume of sheaves therein throwing said member to sheaf discharging position.
- 40 18. In a shocking machine, an upwardly and rearwardly movable tilting sheaf re-
- ceiving member, rearwardly movable means disposed in front of said sheaf receiving member for carrying sheaves into a prostrate position therein, means controlled by the volume of the sheaves therein actuating said member to discharge the sheaves therefrom, and means independent of said sheaves for positively operating said controlling means.
- 45 19. In a shocking machine, an upwardly and rearwardly tilting sheaf receiving member, mechanism for binding sheaves therein and tilting said member; and means engaged by the sheaves when they have reached a certain volume controlling said mechanism.
- 50 20. In a shocking machine, an upwardly and rearwardly movable tilting sheaf receiving cradle, said cradle being open and unobstructed at the top, means movable downwardly through said unobstructed top into said cradle for depositing sheaves in a prostrate position therein, means for compressing the sheaves therein and tilting said cradle, and means controlled by the volume of said sheaves controlling said first mentioned means.
- 55 21. In a shocking machine, an upwardly and rearwardly movable tilting sheaf receiving cradle, mechanism for compressing and binding the sheaves therein and tilting said cradle, and means controlled by the height of said sheaves controlling said mechanism.
- 60 22. In a shocking machine, an upwardly and rearwardly movable tilting sheaf receiving member, mechanism including a swinging sheaf delivery member movable in a fore and aft direction for delivering sheaves thereto, and means set in operation by said mechanism and controlled by the bulk of the delivered sheaves controlling the movement of said sheaf receiving member.
- 65 23. In a shocking machine, a sheaf receiving member, means for depositing sheaves prostrate therein with their butts diverging and their heads converging, and automatic means for binding said sheaves into a shock set in operation by said first mentioned means when said sheaves have reached a predetermined bulk.
- 70 24. In a shocking machine, a sheaf receiving member, means for depositing sheaves prostrate therein with their butts diverging and their heads converging, and automatic means for discharging said sheaves into a shock set in operation by said first mentioned means when said sheaves have reached a predetermined bulk.
- 75 25. In a shocking machine, a sheaf receiving member, means for depositing sheaves prostrate therein with their butts diverging and their heads converging, and automatic means for binding and discharging the sheaves into a shock set in operation by said

first mentioned means when said sheaves have reached a predetermined bulk.

26. In a shocking machine, a sheaf receiving member, sheaf delivering mechanism depositing sheaves prostrate therein, means for deflecting the sheaves to opposite sides of the sheaf receiving member and mechanism for binding said sheaves into a shock set in operation by said deflecting means.

10 27. In a shocking machine, a sheaf receiving cradle, a sheaf delivering member coöperating therewith, and movable in a fore and aft direction, means for deflecting said member to opposite sides of said cradle as it delivers the sheaves, and mechanism for discharging the sheaves from said cradle set in operation by said deflecting means.

20 28. In a shocking machine, a sheaf receiving cradle, a sheaf delivering member coöperating therewith, and movable in a fore and aft direction, means for deflecting said member laterally during its movement to sheaf delivering position, and mechanism for compressing the sheaves in said cradle set in operation by said deflecting means.

30 29. In a shocking machine, a sheaf receiving cradle, sheaf delivering mechanism coöperating therewith, mechanism for deflecting the sheaves delivered to said cradle to different sides of said cradle, and means controlled by the bulk of the sheaves in said cradle, and set in operation by said deflecting mechanism, for binding and discharging the sheaves in said cradle.

35 30. In a shocking machine, a normally prostrate tilting sheaf receiving member, mechanism for successively compressing, binding and discharging the sheaves therein in the form of a shock, and means controlled by the volume of the sheaves in said sheaf receiving member controlling said mechanism.

45 31. In a shocking machine, a sheaf delivering member, a sheaf receiving cradle, mechanism for compressing, binding and discharging the sheaves in said cradle, and means for deflecting said sheaf delivering member as it delivers a sheaf to said cradle controlling the operation of said mechanism.

50 32. In a shocking machine, a movable sheaf receiving cradle, a movable sheaf delivery arm coöperating therewith and movable in a fore and aft direction, mechanism for deflecting said arm laterally to different sides of said cradle, and means set in operation by said deflecting mechanism for discharging the sheaves from said cradle.

55 33. In a shocking machine, a sheaf receiving cradle, a sheaf delivery member positioning sheaves prostrate therein, mechanism deflecting said member alternately to different sides of said cradle, and means set in operation by said mechanism and controlled by the bulk of the sheaves in said cradle for discharging the sheaves from said cradle.

34. In a shocking machine, a sheaf receiving cradle, a sheaf delivery arm coöperating therewith, carrying sheaves into prostrate position therein, means for deflecting said arm alternately to opposite sides of said cradle, and means set in operation by said deflecting mechanism controlling the discharge of the sheaves from said cradle.

70 35. In a shocking machine, a sheaf receiving cradle, mechanism delivering sheaves in prostrate position upon opposite sides of said cradle, and means set in operation by said mechanism and controlled by the height of the sheaves in said cradle for binding and discharging the sheaves therein.

80 36. In a shocking machine, a sheaf receiving cradle, mechanism for delivering sheaves in prostrate position upon opposite sides of the same, and means set in operation by said mechanism and controlled by the height of the sheaves in said cradle for compressing, binding and discharging the sheaves therein.

85 37. In a shocking machine, a shock receptacle, shock discharging mechanism, and mechanism including a swinging shock building member for turning sheaves end for end and building a prostrate shock in said receptacle, actuating said discharging mechanism when said shock has reached a predetermined size.

90 38. In a shocking machine, a shock receptacle, shock binding mechanism, and mechanism including a swinging shock building member building a prostrate shock in said shock receptacle and actuating said binding mechanism when said shock in said receptacle has reached a predetermined size.

95 39. In a shocking machine, a shock receptacle, shock binding and discharging mechanism, and mechanism including a swinging shock building member building a prostrate shock in said shock receptacle and actuating said binding and discharging mechanism when said shock in said receptacle has reached a predetermined size.

100 40. In a shocking machine, a movable shock receptacle, an upwardly and rearwardly swinging sheaf delivering member carrying sheaves into prostrate position therein, mechanism for discharging in the form of a shock the sheaves deposited therein, and a positively operated member engaging said sheaves when they have reached a predetermined height in said receptacle controlling said discharging mechanism.

105 41. In a shocking machine, a movable sheaf receiving cradle, a swinging sheaf delivery member movable in a fore and aft direction delivering sheaves in prostrate position in said cradle, mechanism for discharging the sheaves therein, and a movable member engaging said sheaves when they have reached a predetermined height controlling said discharging mechanism.

110 42. In a shocking machine, a movable

sheaf receiving cradle, a swinging sheaf delivery member delivering sheaves in prostrate position in said cradle, mechanism for binding the sheaves therein, and a movable member engaging said sheaves when they have reached a predetermined height controlling said binding mechanism.

43. In a shocking machine, a movable sheaf receiving cradle, a swinging sheaf delivery member movable in a fore and aft direction delivering sheaves in prostrate position in said cradle, means for compressing the sheaves therein, and a movable member engaging said sheaves when they have reached a predetermined height controlling said compressing mechanism.

44. In a shocking machine, a movable sheaf receiving cradle, a swinging sheaf delivery member delivering sheaves in prostrate position in said cradle, means for compressing, binding and discharging the sheaves therein, and a movable member engaging said sheaves when they have reached a predetermined height controlling said binding and discharging mechanism.

45. In a shocking machine, a sheaf receiving cradle, mechanism for positively positioning sheaves prostrate upon opposite sides of said cradle, and means set in operation by said mechanism and controlled by the height of the sheaves in said cradle for discharging said sheaves therefrom.

46. In a shocking machine, a sheaf receiving cradle, mechanism for positively placing sheaves in prostrate position upon opposite sides of said cradle, and means for binding said sheaves therein set in operation by said mechanism and controlled by a predetermined height of the sheaves in said cradle.

47. In a shocking machine, a sheaf receiving cradle, mechanism for positively positioning sheaves in prostrate position upon opposite sides of said cradle, and means set in operation by said mechanism and controlled by the height of the sheaves in said cradle for compressing the same.

48. In a shocking machine, a sheaf receiving cradle, mechanism including a swinging sheaf delivery member delivering sheaves in prostrate position upon opposite sides of said cradle, and means set in operation by said mechanism and controlled by the height of the sheaves in said cradle for binding the sheaves therein.

49. In a shocking machine, a sheaf receiving cradle, mechanism including a swinging sheaf delivery member delivering sheaves in prostrate position upon opposite sides of said cradle, and means set in operation by said mechanism and controlled by the height of the sheaves in said cradle for compressing and binding the sheaves therein.

50. In a shocking machine, a movable

sheaf receiving cradle, a swinging sheaf delivery member delivering sheaves in prostrate position therein, means for binding and discharging the sheaves therein, and a movable member engaging the sheaves in said cradle when they have reached a predetermined height controlling said binding and discharging mechanism.

51. In a shocking machine, a sheaf receiving cradle, a sheaf delivering member co-operating therewith, mechanism for deflecting said member laterally during its movement to sheaf delivering position, and mechanism for binding and discharging the sheaves in said cradle controlled by said deflecting mechanism.

52. In a shocking machine, a frame, a sheaf delivery arm pivoted thereto, means for oscillating said arm about its pivot on said frame, and means connected to said arm and said oscillating means for deflecting said arm laterally in the course of each oscillation thereof and for guiding the same throughout its oscillatory movement.

53. In a shocking machine, a pivoted sheaf delivery arm, mechanism oscillating said arm about its pivot, and mechanism for deflecting said arm laterally during each oscillation thereof and for positively controlling the path of movement of said arm, said mechanisms being connected to each other through the medium of said delivery arm.

54. In a shocking machine, a pivoted sheaf delivery arm movable in a fore and aft direction, power connections for swinging said arm alternately in opposite directions about its pivot, and link connections intermediate said arm and said power connections and operatively connected to the latter during its fore and aft movement deflecting said arm laterally in the course of each oscillation thereof.

55. In a shocking machine, a pivoted sheaf delivery arm, mechanism for moving the same from a horizontal to a vertical position, and means connecting said mechanism and said arm and guiding the same during its entire path of movement and operated by said mechanism for deflecting said arm laterally as it moves about its pivot.

56. In a shocking machine, a pivoted sheaf delivery arm, mechanism for oscillating the same about its pivot, and means connecting said mechanism and said arm and positively driven by said mechanism for deflecting said arm laterally in the course of each oscillation thereof, said means and mechanism automatically returning said arm to its initial position through substantially the same path.

57. In a shocking machine, a frame, a sheaf delivery arm pivoted thereon, mechanism for oscillating the same about its pivot, and means including a swinging sub-

stantially U-shaped member operatively connected to said oscillating mechanism and said delivery member for deflecting the latter laterally as it moves to sheaf delivering position.

58. In a shocking machine, a frame, a sheaf delivery arm pivoted thereon, mechanism for oscillating the same about its pivot, a swinging upstanding guide carried 10 on said frame, operative connections between one end of said guide and said oscillating mechanism for swinging the former, and a sliding connection between said guide and said delivery member for deflecting the 15 latter laterally as it moves to sheaf delivering position.

59. In a shocking machine, a frame, a swinging sheaf delivery member pivoted thereon, mechanism for swinging the same 20 about its pivot, an upstanding guiding bail pivoted on the frame and movable laterally 25 about its pivot, mechanism operatively connecting said guiding bail to said swinging mechanism for intermittently swinging said bail about its pivot, and operative connections between said guiding bail and said delivery member whereby as the former is deflected the latter is moved therewith.

60. In a shocking machine, a movable 30 sheaf receiving cradle, a swinging sheaf delivery member delivering sheaves thereto, mechanism for deflecting said member to opposite sides of said cradle as it delivers the sheaves, mechanism including a feeler 35 arm operable by said deflecting mechanism to dip into the cradle upon the delivery of every second sheave thereto, and mechanism for discharging the sheaves in said cradle controlled by said last mentioned mechanism.

61. In a shocking machine, a movable sheaf receiving cradle, a swinging sheaf delivery member delivering sheaves thereto, mechanism for deflecting said member to 45 opposite sides of said cradle as it delivers sheaves thereto, mechanism including a feeler arm operable by said deflecting mechanism to dip into one side of said cradle when said delivery member is delivering a 50 sheaf to the opposite side thereof, and means for discharging the sheaves from said cradle controlled by said last mentioned mechanism.

62. In a shocking machine, a frame, a 55 shaft journaled thereon, a pivoted substantially U-shaped member projecting substantially at right angles to said frame, a sheaf delivery member fixed to said shaft and rotatable therewith, automatic means for deflecting said U-shaped member about its pivot alternately in opposite directions, and connections between said delivery member and said U-shaped member for automatically imparting the deflection of the latter 60 to said delivery member.

63. In a shocking machine, a frame, a shaft journaled thereon, a power connection for rotating said shaft, a second shaft journaled on said frame, power connections imparting the rotation of said first mentioned 70 shaft to said second mentioned shaft, a sheaf delivering arm movable with one of said shafts upon the rotation of the other on said frame, and connections between said first mentioned shaft and said arm deflecting 75 the latter laterally as it is rotated.

64. In a shocking machine, a frame, a shaft journaled thereon, power connections for rotating the same, a second shaft carried by said frame, a sheaf delivering arm rotatable with one of said shafts, and means operatively connecting said arm to said first mentioned shaft including a plurality of 80 pinions, and a pivoted member connected to said arm deflecting said arm laterally 85 as it is rotated.

65. In a shocking machine, a pivoted sheaf delivering member, mechanism for oscillating the same about its pivot in opposite directions, and mechanism including a plurality of springs coöperating with said oscillating mechanism for cushioning said member at the limits of its travel and accelerating the return of the same therefrom.

66. In a shocking machine, a swinging 95 shock building member movable through a path of decreasing length as it builds a shock, means for deflecting said member laterally as it moves to sheaf delivering position, and automatic mechanism coöperating therewith for discharging the shock built thereby when the same has reached a predetermined size.

67. In a shocking machine, a swinging 105 shock building member movable through an arc of gradually decreasing amplitude as it builds a shock, mechanism for deflecting said member laterally as it moves to sheaf delivering position, and automatic mechanism for binding and discharging the shock 110 built by said member when said shock has reached a predetermined size.

68. In a shocker, the combination with a shock-assembling receptacle, means for depositing bundles successively in said receptacle, means for tying said bundles in a shock, and means, automatically operated when bundles have accumulated in said receptacle to a predetermined height, for causing the actuation of said shock-tying means. 120

69. In a shocker, the combination with a shock-assembling receptacle, means for depositing bundles successively in said receptacle, means for tying said bundles in a shock, a tripping arm arranged to be tripped when bundles have accumulated in said receptacle to a predetermined height, and mechanism controlled thereby for controlling the actuation of said shock-tying means. 125

70. In a shocking machine, a shock re- 130

ceptacle, a sheaf delivery member delivering sheaves thereto, means for binding the sheaves into a shock automatically operative when the shock has reached a predetermined size, and means under the control of said binding means for preventing the operation of said delivery member during the operation of the binding mechanism.

71. In a shocking machine, a shock receptacle, means for delivering sheaves thereto, shock discharging mechanism automatically operative when the shock has reached a predetermined bulk, and means under the control of said discharging mechanism for preventing the operation of the sheaf delivery member during the operation of the discharging mechanism.

72. In a shocking machine, a movable sheaf delivery arm, means to accelerate said arm during the major portion of its sheaf delivery movement and cushion said arm as it returns to sheaf receiving position.

73. In a shocking machine, a movable sheaf delivery arm, means to accelerate said arm during the major portion of its sheaf delivery movement, means to accelerate the return movement of said arm, and means to cushion said arm at the extremities of its sheaf receiving and sheaf delivering movements.

Copies of this patent may be obtained for five cents each, by addressing the "Commissioner of Patents, Washington, D. C."

Witnesses:

V. D. LAWLER,
R. B. HITCHCOCK.

CLEMMA R. RANEY.

74. In a shocking machine, a frame, a shaft journaled thereon, an arcuate member pivoted about one of its legs, a sheaf delivery arm fixed to said shaft and slidably connected to said arcuate member, means to oscillate said shaft to throw said delivery arm forward and back, and means connecting said arcuate member with said oscillating means and deflecting said member about its pivot alternately in opposite directions.

75. In a shocking machine, a frame, a shaft journaled in said frame, a sheaf delivery arm fixed to said shaft, a collar having spaced abutments fixed to said shaft, a crank arm loosely mounted on said shaft between said abutments, and means for rotating said crank arm.

76. In a shocking machine, a frame, a shaft journaled on said frame, a sheaf delivery member mounted on said shaft, and means including a collar having spaced abutments for oscillating said shaft.

In testimony whereof I affix my signature, in the presence of two witnesses.
